UNITED STATES PATENT OFFICE.

GEORGE A. FREDENBURGH, OF PAWTUCKET, RHODE ISLAND.

TWISTING-HEAD FOR THREAD-DRESSING MACHINES.

SPECIFICATION forming part of Letters Patent No. 731,883, dated June 23, 1903.

Application filed December 24, 1902. Serial No. 136,461. (No model.)

To all whom it may concern:

Be it known that I, GEORGE A. FREDENBURGH, a citizen of the United States, residing at the city of Pawtucket, in the county of Providence and State of Rhode Island, have invented a certain new and useful Improvement in Twisting-Heads for Thread-Dressing Machines, of which the following is a specification.

10 My invention relates to a twisting-head adapted for a thread-dressing machine; and the object of my invention is to provide a thread-twisting device of simple and compact construction, so that a large number of 15 twisters may be mounted on the said machine, each twisting-head twister operated independent of the other and each twisting-head twister provided with means for the ready insertion of a thread in case of breakage during the running of the machine.

The invention consists of the novel construction and combination of the several parts, as hereinafter described, and specifically set forth in the claims.

20 In the accompanying drawings, Figure 1 represents a front sectional elevation view of a thread-twister embodying my improvement, taken in line XX of Fig. 2. Fig. 2 is a view, partly in section and partly in elevation, of the twister-head, taken in line YY of Fig. 3. Fig. 3 is a top plan view of a series of twisting-heads as mounted in brackets secured to the machine-frame, and also showing each twisting-head twister provided 25 with a shipping-lever. Fig. 4 is a top plan view of the front end portion of the bracket provided with a circular channel arranged to receive rollers for the twisting-head; and Fig. 5 is a partial top plan view, taken in ZZ of Fig. 2, of the front portion of the bracket with its stud-shaft mounted thereon and the gear for rotating said stud-shaft, and also showing the slot arrangement for the insertion of the thread to be twisted.

30 Similar letters of reference designate corresponding parts in the several views.

In the drawings, A indicates a shaft by which the twisting-head is driven, and this shaft is rotatably mounted longitudinally on the frame of the machine and is revolved by suitable means thereon. This driving-shaft is provided with a spline b, which extends

throughout its length. A beveled gear c is slidably mounted on the shaft A and has a hub c' with a peripheral groove in which a 55 shipping-lever d is supported, and said shipping-lever is pivoted on a bolt d', which is secured in a projecting ear d'' of the machine-frame B.

e is a bracket, which has one end rigidly secured to the machine-frame by a bolt f, and this bracket extends horizontally from the machine-frame, and near its outer or front end is provided a circular vertical opening g, and in the upper surface of the said 65 bracket e and concentric to its opening g is formed a V-shaped channel or ball-bearing g'. The bracket e is further provided with a narrow slot g'', extending longitudinally through from the front end of the bracket 70 and entering the opening g in the manner as seen in Fig. 4.

h is a circular ball-bearing head having a centrally-projecting shank h' integral therewith and adapted to fit loosely in the circular 75 opening g of the said bracket e, and this circular head is provided with a V-shaped channel or ball-bearing h'', formed in its inner or bottom surface and so arranged that when the head h is mounted in position upon the 80 bracket e its channel h'' will be inverted to that of the first-named channel g' of the bracket and of the same size and location with the channel in the same, thus forming bearing-surfaces for ball-rollers i i. The head 85 h and its shank h' is further provided with a narrow radial slot g'', extending through to the axial center thereof, as shown in Figs. 2 and 5. Wire arms j and j' are mounted and rigidly secured upon the upper surface of the 90 head h by screws k k, which enter the same, and one of said arms, which extends vertically from the head h, has a small circularly-bent thread-eye l, situated concentric to the axial center of the head h, while the other wire 95 arm j', which is one-half the height of the first-named arm, has a similar thread-eye l', whose center is offset from the center of the said head h and to the rear of the slot g'' in the same.

c'' is a beveled gear, which is keyed or otherwise secured to the shank h' of the head h, and said gear is provided with a narrow radial slot g'', which extends to the axial center

thereof, as shown in Figs. 2 and 5. The radial slots g^3 and g^4 of the said head h and its shank and said gear c^2 come in alinement with the slot g^2 of the bracket e , as seen in Fig. 5, so that a thread m can pass through all of said slots to a central position, and from these slots the thread passes through the eye l' of the offset arm j' , situated to the rear of the slot g^3 in the head h , as shown in Fig. 2, and from the thread-eye l' the thread passes up through the thread-eye l of the arm j , which directs the thread again to its vertical position centrally of the twisting-head h , as shown in said figure, and from the thread-eye l the thread is carried up to the brush-cylinders and ironer-cylinders, (not shown,) and which cylinders perform the operation of laying the fibers and polishing preparatory to finishing the thread. The thread m comes up from a sizing box or trough (not shown) situated below the hereinbefore-described twisting-head, and in order to have the thread move centrally of the said twisting-head and without its coming in contact with the driving-shaft.

25 A the teeth of the beveled gears c and c^2 are made to extend at an offset radially from the axial center of the said gears, so that an offset is provided between the surface of the said shaft A and the center of the said twisting-head, thus permitting a free space or clearance for the vertical movement of the thread to the twisting-head in the manner as shown in Fig. 2. By having the thread-eye l' of the wire arm j' located at an offset from the vertical center of the twisting-head causes the thread to bear against the edge at the inner end of the slot in the twisting-head h at a point m' , whereby the twist is formed in the thread up from this point in the said twisting-head through the rotative movement of the gear c^2 , which meshes with the gear c' of the driving-shaft, and, furthermore, by having the said thread-eye l' offset, as described, prevents the thread m from leaving the slot g^3 during the rotation of the twisting-head. The speed of rotation of the twisting-head is much greater than that of the movement of the thread, and by having the ball-rollers interposed between the circular head h and its bracket e the amount of friction caused by the fast revolving speed of the said circular head is much lessened.

When a thread breaks during the running of the machine, all that is required on the part of the operator is to throw back the shipping-lever d , which movement will carry the slideable gear c' from engagement with the gear c^2 , (see Fig. 3,) after which he will rotate the latter gear to bring its slot g^4 and the slot g^3 in its circular head in alinement with the slot g^2 of the bracket to the position as indicated in Fig. 5. The thread is then tied and replaced in the slots and the twisting-head again started.

65 From this description of the slot arrangement for a thread-twisting head it will be observed that the thread can be quickly insert-

ed or taken out of the twister, as the case may require.

This construction of a thread-twister mechanism forms a very simple and compact arrangement of parts adapted for a thread-dressing machine, inasmuch as a large number of twisters can be mounted consecutively upon the machine-frame, and each twister 70 being independent of the other and provided each with a shipping-lever for throwing into or out of engagement with the driving-shaft.

This invention is an improvement upon the thread-dressing machine shown and described 80 in Letters Patent of the United States, No. 702,786, issued to me June 17, 1902.

I claim as a novel and useful invention and desire to secure by Letters Patent—

1. In a twisting-head for a thread-dressing machine, a device consisting of a bracket rigidly secured to the machine-frame and provided with a longitudinal slot extending from the front end of said bracket, and entering a vertical circular opening formed in the same; 90 a rotatable head mounted on said bracket and having a centrally-projecting stud-shaft integral therewith and loosely entering through the circular opening of said bracket; a beveled gear rigidly secured upon the stud-shaft of said head; said head and its stud-shaft and said gear being radially slotted to allow the passage of a thread to its geometrical center, two vertical arms rigidly secured upon said head and having a thread-eye at each upper portion thereof; one of said arms made longer than the other and whose thread-eye is centrally with the axial center of said head, while the thread-eye of the other or shorter arm is offset to the rear 100 of the slot in the same, and so arranged that the eye of the shorter arm guides the thread in a zigzag course from the closed end portion of the slot in said head to its central position in the eye of the longer arm, and means 110 to operate the rotative parts of the device, substantially as set forth.

2. In a twisting-head for a thread-dressing machine, the combination of a shaft rotatably mounted on the machine-frame and provided with a longitudinal spline; a beveled gear slidably mounted on said shaft; a bracket rigidly secured to the machine-frame and provided with a longitudinal slot which enters a vertical circular opening formed in said bracket; a rotatable stud-shaft mounted in the opening of said bracket and having an enlarged circular head integral at one end thereof; a beveled gear rigidly secured at the other end of said stud-shaft; said stud-shaft 125 and its head and said last-named gear having a radial slot to allow the passage of a thread to their axial center, a thread-guide fixed upon the circular head of said stud-shaft and arranged to direct the thread in a diagonal course from the opening in the axial center of the said circular head; a second thread-guide fixed upon the head of said stud-shaft and arranged to direct the thread from the 130

first said guide to the axial center of said head; and a shipping-lever pivoted on the machine-frame and arranged to disconnect the two beveled gears, substantially as specified.

5 3. In a twisting-head for a thread-dressing machine, the combination of a horizontal shaft rotatably mounted on the machine-frame and having a longitudinal spline; a beveled gear 10 slidable on said shaft and having its teeth radially offset from the longitudinal center thereof; a bracket rigidly secured to the machine-frame and provided with a circular V-shaped channel in its upper surface; a vertical stud-shaft mounted in said bracket and having a circular head integral therewith and provided with a V-shaped channel in its lower surface of the same size and location as the first-named channel; roller-balls mounted in 15 the channels of said bracket and head of said stud-shaft; a beveled gear rigid on said stud-shaft and having its teeth radially offset from the longitudinal center thereof; said bracket, said stud-shaft and its head, and said last-named gear provided each with a slot to allow the insertion of a thread, a thread-guide rigid upon the circular head of said stud-shaft and arranged to direct the thread in a 20 diagonal course from the opening in the axial center of the said circular head; a thread-guide rigid upon the circular head of said stud-shaft and arranged to direct the thread from the first said guide to the axial center of said head; and a shipping-lever arranged

to disconnect the said two beveled gears, substantially as shown and described.

4. In a twisting-head for a thread-dressing machine, the combination of a shaft rotatably mounted on the machine-frame and provided with a longitudinal spline, a beveled gear 40 slidable mounted on said shaft, a bracket rigidly secured to the machine-frame and provided with a longitudinal slot which enters a vertical circular opening formed in said bracket, a rotatable stud-shaft mounted in 45 the opening of said bracket and having an enlarged circular head or flange integral at one end thereof, a beveled gear rigidly secured at the other end of the stud-shaft, said stud-shaft and its flange and said last-named gear having a radial slot to its axial center, each 50 of said slots to allow the passage of a thread, a thread-guide fixed upon the flange of said stud-shaft and arranged to direct the thread in a diagonal course from the opening in the 55 axial center of the said circular head, another thread-guide fixed upon the flange of said head and arranged to direct the thread from the guide to the axial center of said head, and a shipping-lever pivoted on the machine-frame and arranged to disconnect the two bevel-gears, substantially as specified.

In testimony whereof I affix my signature in presence of two witnesses.

GEORGE A. FREDENBURGH.
